United States Patent Office

Des. 191,257
Patented Sept. 5, 1961

191,257

RING BINDER

Seymour Mace Cole, Glencoe, and Paul I. Dale, Wilmette, Ill., assignors to Feldeco, Inc., Chicago, Ill.,
a corporation of Illinois

Filed Feb. 2, 1960, Ser. No. 59,233

Term of patent 14 years

(Cl. D6—2)

Fig. 1.

Fig. 2.

We claim:

The ornamental design for a ring binder, as shown and described.
